ADJUSTABLE PLIERS

Howard H. Manning, Meadville, Pa., assignor to
Champion De Arment Tool Company, Mead-
ville, Pa., a corporation of Pennsylvania

Application August 4, 1949, Serial No. 108,578

2 Claims. (Cl. 81—51.3)

1

This invention relates to hand tools, such as pliers, having members pivoted by tongue and groove joint elements. In a preferred form there are a plurality of joint elements on one of the members which are selectively usable for different jaw openings. Such tools, under working conditions, are subject to heavy stresses. This invention is intended to improve the working strength by terminating the joint elements short of the edge subject to tension stress. This provides a higher effective strength under working conditions without increasing the weight. Further objects and advantages appear in the specification and claims.

In the drawing, Fig. 1 is a side view of a pair of pliers; Fig. 2 is a section on line 2—2 of Fig. 1; Fig. 3 is a fragmentary view of a section having higher working strength; Fig. 4 is a fragmentary view of another section having higher working strength, and Fig. 5 is a section on line 5—5 of Fig. 4.

The invention is shown applied to a tool of the construction illustrated in my Patent 1,950,362. As there shown the tool comprises pivoted members 1 and 2 respectively provided with jaws 3 and 4 offset to one side of a bolt 5 extending through an opening 6 in the member 2, and a slot 7 in the member 1. On the opposite side of the bolt the members are provided with handles 8 and 9. On the member 2 is an arcuate rib 10 receivable in anyone of a plurality of arcuate grooves 11 in the member 1, the grooves being defined by ribs 11a some of which are in the range of the slot 7. The width of the jaw opening is adjusted by sliding the bolt 5 along the slot 7 until the rib 10 comes opposite the desired groove 11. From one aspect the rib 10 and groove 11 are tongue and groove joint elements. The parts so far described are shown in greater detail in my aforesaid patent.

Under working conditions the reaction forces on the jaw 3 stress the edge 12 of the member 1 in compression and the edge 13 of the member 1 in tension. Because the tension edge 13 is interrupted by the grooves 11, there are points of stress concentration which are greatest at the points 14 where the corners of grooves 11 intersect the tension edge 13. At the points 14 there is an abrupt change in the width of the tension edge 13. While the stress concentration is objectionable under static loads, it is particularly objectionable under the working loads encountered in pliers which are of the nature of suddenly applied or impact loads.

It is found that the working strength of the

2

pliers can be substantially doubled if the ends 15 of the ribs 11a adjacent the tension edge 13 are cut off so as to make the tension edge continuous. By doing this the ribs 11a defining the grooves 11 terminate short of the tension edge and there are no points of stress concentration at which failure can start. In other words, by removing some of the metal heretofore considered necessary, the working strength of the pliers is increased. Since the weakest section of the pliers is that opposite the slot 7, it is particularly desirable that the ends 15 of the ribs 11a be cut off in this region. In a preferred form shown in Fig. 4 the tension edge 13 comprises a longitudinal rib 16 having its upper surface at or slightly below the base of the grooves 11. Since the plier members are usually made of forgings it is more convenient to have the upper surface of the rib 16 below the base of the grooves 11. In both cases the highly stressed tension edge 13 is a smooth continuous edge free from points of stress concentration at which fracture can start under working stresses. Whether the elimination of the points of stress concentration is obtained by cutting off the ends 15 of the ribs 11a, or by adding a continuous rib 16, is a matter of design. In either case the strength under impact loads which more closely approximate the working loads in a plier is increased nearly double while the strength under static loads remains essentially the same as the construction illustrated in Fig. 1.

What I claim as new is:

1. In a tool having a pair of crossed members, one having a slot and the other having a pin in the slot, work engaging surfaces on the members offset to one side of the slot, and tongue and groove elements on adjacent faces of the crossed members comprising an arcuate rib on the pin carrying member concentric with the pin and a plurality of arcuate ribs on the slotted member defining a plurality of spaced open ended grooves in any one of which the rib on the pin carrying member is receivable to provide a pivotal connection between the members, at least all of the arcuate ribs on the slotted member in the range of the slot terminating short of the edge of the slotted member on the side from which the work engaging surfaces are offset.
2. In a tool having a pair of crossed members, one having a slot and the other having a pin in the slot, work engaging surfaces on the members offset to one side of the slot, tongue and groove elements on adjacent faces of the crossed members comprising an arcuate rib on the pin carry-

ing member concentric with the pin and a plurality of arcuate ribs on the slotted member defining a plurality of spaced arcuate open ended grooves in the slotted member in any one of which the rib on the pin carrying member is receivable to provide a pivotal connection between the members, and a longitudinal rib on the edge of the slotted member toward the work engaging surfaces having its upper surface at or below the bottom of the arcuate ribs defining the 10 grooves on the slotted member, and the ends of the arcuate ribs on the slotted member terminating short of the longitudinal rib.

HOWARD H. MANNING.
